UNITED STATES PATENT OFFICE.

WILLIAM J. RYTHON AND BERT A. COLE, OF ST. PAUL, MINNESOTA,
ASSIGNORS TO THE SMITH PREMIER TYPEWRITER COMPANY, OF
SYRACUSE, NEW YORK.

ATTACHMENT FOR TYPE-WRITERS.

SPECIFICATION forming part of Letters Patent No. 679,785, dated August 6, 1901.

Application filed November 22, 1899. Serial No. 737,858. (No model.)

To all whom it may concern:

Be it known that we, WILLIAM J. RYTHON and BERT A. COLE, citizens of the United States, residing at St. Paul, in the county of 5 Ramsey and State of Minnesota, have invented certain new and useful Improvements in Attachments for Type-Writers, of which the following is a specification.

Our invention pertains to attachments for 10 type-writing machines, and is designed for ready application to the platen of type-writing machines of any usual style or construction to hold in position on the platen cards, envelopes, and other comparatively small 15 pieces or objects upon which it is desired to write.

Among objects sought to be attained by this 20 invention are facility of application and removal of the device to and from the platen of the type-writing machine; firm and secure holding of the card, envelop, or other device along its entire top or edge and regardless of the space in the length of the attachment occupied by such card, envelop, or the like; to insure 25 the firm retention of the device in place, and to avoid the presence of projections or overhanging portions extending materially inward from the clamped edge of the card, envelop, or other article, where they might be struck by the type of the machine, or the 30 presence of any portion of the attachment beneath the paper, card, or envelop.

Our improved device is illustrated in the accompanying drawings, wherein—

35 Figure 1 is a perspective view of the attachment removed from the platen; Fig. 2, a perspective view of the platen with the attachment in place thereon and with a card or half-sheet clamped thereunder; Fig. 3, a 40 transverse sectional view through the platen and attachment, showing the edge of a card or sheet inserted thereunder and showing also a pressure-roller and card or envelop guide used in certain well-known type-writing 45 machines, though not constituting a part of the present invention nor necessarily used therewith; and Fig. 4, a similar view, but with the platen turned to bring the paper to printing position.

In the practical use of type-writing machines it frequently happens that small slips, cards, envelopes, and the like require to be printed, and more or less difficulty has been experienced in properly holding the same upon the platen and presenting them to the printing characters. The present invention aims to overcome this difficulty in a simple and efficient manner.

To this end the attachment consists of a narrow strip 3 of metal or equivalent material of a more or less resilient nature curved or bowed facewise in the direction of its length and formed or provided at each end with lateral gripping-arms which are bent or curved into hoop or ring form, as shown in the several figures of the accompanying drawings. The arms 2 being of the same character as the strip 3—that is to say, of a somewhat resilient nature—and bent into the form indicated, constitute spring-clasps or gripping-arms, which may be opened sufficiently to be passed over or about platen A and which when in position thereon will contract sufficiently to clamp or bind the device firmly to or upon the platen. Owing to their form, constituting an extended arc of a circle, which when the device is detached from the platen should be of somewhat less radius than the platen A, the arms will tend to hug the platen closely and to make contact therewith at all points in their length or surface, this force being sufficient to overcome the outward pressure incident to the longitudinal bowing of the strip 3 because of the shorter length of the arms measured from the point of connection with or branching from the strip 3. The bowed or curved form of the strip 3 insures initial contact of the strip at its mid-length with the platen and from that point to the arms 2, provided said arms hug the platen closely and draw the ends of the strip 3 down against the platen, as explained. It will be seen that the bowing of the strip 3 is a matter of some practical importance, in that it insures a firm hold of even a short or narrow card or paper introduced between the strip 3 and the platen A at any point in the length of said strip, whereas without such provision

there is always a tendency or liability of the clamping-strip to hold more firmly at the ends or at one end than near the middle.

As shown in Fig. 1, the ends of the gripping-arms 2 are turned inward toward each other, and being rounded at their extremities they terminate in a comparatively narrow and somewhat sharp edge, which causes them to embed themselves slightly in the yielding surface of the platen, and thereby to prevent slipping of the device upon or relatively to the platen either longitudinally or circumferentially.

While we do not mean to restrict ourselves arbitrarily to the proportions shown in the drawings, it is nevertheless very desirable that the arms 2 at each end of strip 3 shall extend more than half-way around the platen, the drawings indicating approximately three-quarters of a circle, and such measurement being desirable in order that the free ends of the arms may extend far enough around the side of the platen opposite the strip 3 to firmly draw said strip down against the platen and hold it. Without spurs or equivalent devices something more than a half-circle will be necessary for the length of the arms 2, though with the free ends of the arms curved inward toward each other, so that their ends may embed themselves slightly in the platen, as indicated, it is possible even with only a half-circle to retain the device in place with measurable firmness. As indicated, however, it is deemed preferable, and, in fact, important, to make the arms reach through more than half a circle.

On account of simplicity and cheapness of construction and for other reasons it is preferred to make the arms 2 integral with the strip 3, and thereby to avoid the necessity of brazing, soldering, or riveting the parts together. We do not, however, restrict ourselves to the integral construction. In whatever way formed, however, it is deemed desirable that the strip 3 be arranged to bear directly against the platen and that the paper, card, or other device enter beneath the strip 3 or between it and the platen in order that there may be perfect contact of the card or paper with the platen and that it may be smoothly and firmly held thereto.

It will be observed that under the construction here shown and described the device may be quickly and easily pressed or sprung to place upon the platen, as shown in Fig. 2, and that a card or sheet may be conveniently and easily inserted beneath said strip by simply lifting the same slightly by the thumb-nail or in any convenient way, or the paper or card may be laid upon the platen and the holder sprung to place over and upon it. It will be noted, too, that there are no fingers, arms, or projections of any kind reaching from the strip or bar 3 downward over or across the face of the card, envelop, or sheet and that consequently there is nothing which might by engagement with the type interfere with the

proper travel of the carriage or platen or by coming in the path of the type cause them to be injured or battered.

In using the attachment the platen is brought to the position indicated in Figs. 2 and 3, the bar 3 is lifted or sprung upward sufficiently to permit insertion of the top edge of the sheet, card, or envelop, and the platen is then rotated to bring the proper portion of the card, sheet, or envelop to position to receive the impression of the type or printing characters. This position will of course vary according to the class or character of type-writing machine on which the attachment is used.

In Figs. 3 and 4 the pressure-roller 5 and guide-roller 6, guide-arm 7, front carriage-bar 8, and adjusting-screws 9 and 10 of the well-known Remington machine are illustrated. These serve as the platen is rotated to curve the paper about and hold it in contact with the platen; but we do not restrict ourselves to the employment of these devices, nor, in fact, to any guiding or pressure devices, as it is possible to use the clamp or attachment without such. As before indicated, however, the device is intended for use with any ordinary type-writing machines and will be employed in connection with such guiding devices thereof as it may be deemed advisable to retain or use.

In the drawings the arms 2 are represented as extending both ways from the strip 3; but this is not essential. They may be in this form wholly at one side of the connecting-strip or may project unequally from opposite sides thereof, the material point being that they extend sufficiently about the platen to insure proper retention of the device thereon. So, too, we have shown and mentioned the longitudinal bowing of the strip 3. While this is preferred for the reasons noted, it is not absolutely required or essential, and a device otherwise in accordance with our invention, but omitting this bowing or curvature, we should regard as within our claims.

Having thus described our invention, what we claim is—

1. A card or slip holding attachment for type-writers, comprising a longitudinal bar or strip adapted to bear directly upon the platen, and spring-arms at opposite ends of said strip adapted to pass around somewhat more than half the circumference of the platen, and by the spring action of said arms to draw and hold the connecting-bar firmly in contact with the platen.

2. An attachment for type-writing machines, comprising a pair of spring-clamps adapted to partially encircle and to firmly clasp a platen or paper-roll; and a connecting-strip extending from one clasp to the other and adapted to receive beneath it and to clamp or bind directly upon the platen, a card, slip, or other body to be printed.

3. An attachment for type-writing machines, comprising a longitudinal bar to press

- and hold a card, sheet, or slip against the platen or paper-roll; and spring-clamps of arc shape carried by the ends of said strip and having their extremities bent inward 5 toward each other, substantially as described and shown, whereby they are caused to embed themselves slightly in the surface of the platen and thereby prevent accidental displacement.
- 10 4. An attachment for type-writing machines, comprising a longitudinal bar and spring clamping-arms carried at the ends of said bar and adapted to partially encircle the platen or paper-roll, and by their inward pressing 15 sure to draw and hold the connecting-bar closely to the platen and to bind between said
- strip or bar and the platen, a card, slip, or other object to be printed, the bar being without projections of any kind above or below the paper, beyond the face of the binding or 20 clamping strip.
5. A device of the class described, consisting of a pair of curved spring-arms, and a strip connecting said arms, said strip being inwardly curved as shown. 25
- In testimony whereof we affix our signatures in presence of two witnesses.
